UNITED STATES PATENT OFFICE

HUBBARD G. PARKER, OF BURLINGAME, CALIFORNIA, ASSIGNOR TO STANDARD STATIONS, INC., OF SAN FRANCISCO, CALIFORNIA, A CORPORATION OF DELAWARE

DESIGN FOR A PEDESTAL DESK

Application filed October 14, 1932. Serial No. 45,368. Term of patent 14 years.

To all whom it may concern:

Be it known that I, HUBBARD G. PARKER, a citizen of the United States of America, residing in the city of Burlingame and county of San Mateo, State of California, have invented a new, original, and ornamental Design for a Pedestal Desk, of which the following is a specification, reference being had to the accompanying drawing, forming part thereof.

In the drawing the figure is a perspective view of a pedestal desk showing my new design.

I claim:

The ornamental design for a pedestal desk, as shown.

Signed at San Francisco, California, the seventh day of October, 1932.

HUBBARD G. PARKER.
